UNITED STATES PATENT OFFICE.

FRANK E. WELLMAN, OF KANSAS CITY, KANSAS, ASSIGNOR TO THE KANSAS CITY GASOLINE COMPANY, OF KANSAS CITY, KANSAS, A CORPORATION OF KANSAS.

METHOD OF HEATING OIL.

Original application filed December 15, 1921, Serial No. 523,062. Divided and this application filed January 30, 1922, Serial No. 532,873. Renewed February 12, 1926.

To all whom it may concern:

Be it known that I, FRANK E. WELLMAN, a citizen of the United States of America, residing at Kansas City, in the county of Wyandotte and State of Kansas, have invented a certain new and useful Improvement in Methods of Heating Oil, of which the following is a specification, reference being had thereto to the accompanying drawing.

My invention relates to the treatment of oils, with particular reference to methods of heating oil stills and retorts. It has for its object to provide an efficient method of heating a body of oil to cracking temperature and maintaining said temperature without injurious effects of local overheating of the shell of the container from constant impingement of heat at one point, and without destructive precipitation and burning on of carbon deposits. I attain this object by supporting the container with its sides vertical, and applying the heat to said sides at constantly changing points, while maintaining a non-heated section to receive the precipitated carbon, preferably from the bottom of the container to a point a predetermined distance above the same.

I shall describe herein apparatus for practicing the method by rotating a burner or jet around a cylindrical still set with its axis substantially vertical, while maintaining a non-heated section at the bottom thereof by means of a mechanical shield or shelf rotating with the burner. However, the apparatus for practicing the method may be varied by those skilled in the art without departing from the spirit of the invention, the gist of which lies in applying heat at constantly changing points while maintaining a nonheated section to receive precipitated carbon.

One form of apparatus for practicing my invention is illustrated in the accompanying drawings in which:

Fig. 1 is a vertical central section, diagrammatic in character, of a cylindrical still with rotating burner.

Fig. 2 is a similar section of an apparatus found successful in practice, with rotating burner and shelf.

Fig. 3 is a horizontal section taken on the line 3—3 of Fig. 2, looking in the direction of the arrows.

Fig. 4 is a detail view in vertical section of the head of a still fitted with an indicator.

Referring to Fig. 1, the numeral 1 indicates a still of usual cylindrical body, hung by lugs 1^a—1^b in a furnace 2, having a stack 2^a at the top, a space 2^b at the bottom beneath the still, and an annular chamber 2^c between its walls and the sides of the still. The still has a charging and draw-off line as 1^c, a vapor line as 1^d, the former extending nearly to the bottom 1^e, and the latter terminating within the top or crown 1^f. The still is charged with oil to the level shown. The bottom 1^e is insulated with an overlap of the insulation on the sides, as indicated at 1^g, dimensions of course being variable according to conditions. Beneath the still, in the space 2^b, a rotating burner 3 is located. This may have a fuel pipe 3^a, a surrounding air pipe 3^b, and swivelled joints 3^c and 3^d so arranged that the burner 3^e may be swung or rotated in a circle in the annular space 2^c, by means of bevel gears driven by a shaft 3^f connected to suitable motor means 3^m. As the burner 3^e rotates the heated gases will rise therefrom in continuous helical waves 80 around the body of the still 1, the intensity and distribution of the heat being determined by the rate of combustion of the fuel and the speed of rotation of the burner.

Referring to Figs. 2 and 3, the still 1 is hung as before by lugs (not shown) in the furnace 2 so as to leave an annular flue space 2^c provided with stack opening 2^a at the top. In this case 1^a is the draw-off line, 1^b the charging line, and 1^c the vapor line. At the bottom of space 2^c a rotating shelf 8^b is provided, (best shown in Fig. 3,) supported by arms 8^a—8^b on a sleeve 8 having fixed thereto a bevel gear 8^c driven by pinion 8^d on shaft 3^f leading to motor drive indicated as 3^m before by 3ⁿ. The fuel is oil led in through pipe 4, and with it is supplied steam through pipe 5, these two pipes terminating at a common spray nozzle or burner 3^e carried by the shelf 8^b, which has a set of draft openings 8^d (see Fig. 3) to supply air for combustion. To permit rotation of the burner, pipe 4 has a vertical central fixed section fitted at its upper end with a swivel joint 4^a for the rotary section 4^b leading to the burner 3^e; while pipe 5 has a vertical jacket section 5^a surrounding pipe 4 and fitted at its upper end with a swivel joint 5^b for

rotating cap 5^a having a stuffing box around pipe 4, and carrying the rotating pipe 5^a leading to the burner 3^a. The operation is essentially the same as in the apparatus of Fig. 1. The flames and heated gases are confined to the space above the shelf 8^b, and air for combustion is supplied through space 2^b beneath the same. The fuel oil is somewhat preheated by the steam in jacket 5^a, which is an incidental advantage.

In Figure 4 I have shown a gauge glass attached to the head of the still to show the liquid level. This is typical only, as in practice a convenient form of indicator is a float 15 rising and falling on the oil and an indicator arm outside the still, with an operating connection from the float to the arm through a stuffing box. Other forms of indicator may be employed without departure from 20 the invention.

The reason for determining the liquid level with certainty is that this system of heating is intended to enable two contents or more to be pumped in and treated in one 25 run. After such a run, in which there is drawn off through the condenser more than the original charge, the interior of the still is found to bear only a thin coat of carbon, approximately the thickness of a coat of 30 paint, which scrapes off very easily. This is due not only to uniform distribution of the heat over the still body, but to the direct application of the naked flame upon the cylinder of the still at constantly changing 35 points. The vertical position of the still lends itself to this mode of application, as naturally the carbon precipitates from its perpendicular sides.

It will be observed that the arrangement 40 of the burner 3^a and the shelf 8^b in Figs. 2 and 3, enables regulation of the amount of air supplied for carburization of the fuel, and also provides a very convenient means of supporting a target for the oil burner to 45 play over.

It is also to be observed that the figures in the drawing are diagrammatic only, and that many necessary details of construction are omitted for simplicity. Thus in Figure 50 1 no manhole is shown in the container 1, but it is understood that a manhole or manholes are supplied in practice at points convenient for removing the accumulation of carbon from the bottom of the container and for other purposes. Also, in Figure 4, no 55 supply, draw-off, or other pipe line connections are shown, but it is understood that in practice these are supplied of suitable design and at suitable points. Both manhole and 60 pipe line connections are indicated in Figure 2, and it is understood that all known devices, such as draw off or tar cocks or other means for removing, trapping, and handling residuum, means for regulating the air 65 supply to the burner 3^a by closure of open-

ings 8^a or by closure of furnace opening 2^a, target means for the flame of the burner to play against, and the like, as well as any desired mode of connecting and operating the still apart from the heating are contemplated by me and are supposed to be used as good practice requires.

In practice, with this method of heating, I have found, as heretofore stated, that only a very thin coating of carbon adheres to the 70 sides of the still, and that with skilful firing this coating is so thin and so loose it can almost be wiped off with a cloth. I believe therefore, that the limit of operating time may be set, not as heretofore by the amount 75 of carbon on the sides of the still, but by the nature of the still "bottoms"; in other words, it is possible with this method to run as long as the residuum is of a commercial nature. The still "bottoms" eventually reach a point of almost no value, if reduced too far, becoming almost like liquid carbon; but by applying my heat as herein described I am enabled to stop just before this point is reached, without risk, since the 80 safety of still and contents is assured, in any event. With previous methods of heating, this could not be done, because of the risk 85 of sudden precipitation in quantity and burning on of carbon, with resultant destruction of the still bottom.

This application is a division of my prior co-pending application, Serial 523,062, filed Dec. 15, 1921.

What I claim is:

1. The method of cracking oil without liability to burning on the container of precipitated constituents, which consists in maintaining the bottom of the body of oil at a temperature below that at which burning can occur, and applying heat in rotary progression at constantly changing points to said body above the bottom thereof.

2. The method of treating oil in a still or retort, and preventing the burning on of precipitated carbon, which consists in supporting said still or retort with its sides vertical, applying heat to said vertical sides in rotary progression at constantly changing points, and maintaining a non-heated section to receive precipitated carbon, by mechanically shielding the bottom of the still up to a predetermined point.

3. The method of preventing the burning on of carbon in the treatment of oil in a cylindrical still or retort which consists in supporting the still with its axis substantially vertical, heating the vertical sides in rotary progression at constantly changing points, and maintaining a non-heated section to receive precipitated carbon at the bottom end of the cylinder and for a predetermined distance above the same.

4. The method of heating an oil still or retort to avoid the burning on of precipi-

- tated carbon which consists in applying heat directly to different points on the shell of the still in alternating and periodic increments or waves, out of the zone of direct deposition of carbon.
5. The method of heating a vertical oil still which consists in rotating a source of heat around the vertical walls thereof at such regulated intensity and speed as to successively and periodically heat all portions of said walls to maintain a cumulative, cracking temperature without burning at any point.
6. The method of heating a vertical oil still which consists in relating a concentrated high intensity flame to the vertical walls of the still so as to communicate heat directly thereto, and then producing relative movement of the still walls and the heat source so as to cause progressive and periodic heating at constantly changing points.
7. The process of conveying heat energy through a container to a confined body of oil from a source of energy having a temperature destructive to the container without burning the container or burning on carbon, which consists in causing the source to act directly in constantly recurring cycles on successively recurring vertical areas of the container during successive periods of time each less than the period required for destructive action.
8. The method of heating a body by the use of a high intensity source applied thereto which consists in rotating the source continuously with respect to the body and regulating the speed of rotation proportionally to the intensity of the source, so that the sum of the successive increments of energy imparted to any one area of the body in a given time will be less than that required for destructive action in that time.

In testimony whereof I affix my signature.

FRANK E. WELLMAN.
